HEEL DRILLING FIXTURE

Hiram Gordon and Albert C. Rogge, Columbus,
Ohio, assignors to Perma Corporation, Chicago,
Ill., a corporation of Illinois

Application May 23, 1936, Serial No. 81,477

10 Claims. (Cl. 12—42)

This invention relates to an improved heel drilling fixture especially adapted for use in the manufacture of wooden shoe heels of the type which are fastened by nailless means to the heel seats of shoes. Such heel fastening means have been disclosed in the patent to A. G. Eichhorn, No. 2,023,671, issued December 10, 1935, and involve a metallic plate fastened to the heel seat of a shoe and formed with downwardly extending keeper ears which are received within spaced slots extending into the body of a wood heel from the seating surface thereof, the keeper ears being apertured for registration with a complementary bore extending transversely through 10 the heel body from the breast surface thereof, the said bore being adapted for the reception of a locking pin which is driven into said bore so as to occupy openings in the keeper ears of the metallic plate, whereby to prevent separation of 15 the heel from the shoe body.

It is of primary importance in the commercial manufacture of shoes involving heels having the aforesaid manner of attachment that the transverse bore provided in the wood heels should 20 bear accurate relationship with the keepers or ears of the metallic fastening plates, in order that when the locking pin is inserted, the latter will definitely pass through the keepers or ears to secure the desired locking action.

Therefore, it is an object of the present invention to provide a gaging fixture which when a wood heel is clamped or positioned therein, the said heel will be so located as to provide for the accurate drilling or boring of the lock pin receiving opening therein, so that said pin receiving opening will intersect the ear-receiving slots extending from the seating surface of the heel, so that when a pin is subsequently driven into 30 said opening, it will be brought into penetrating 35 contact with the ears of the fastening plates disposed in said slots.

For a further understanding of the invention, reference is to be had to the following description and the accompanying drawing, wherein:

Fig. 1 is a perspective view of the improved drilling fixture comprising the present invention;

Fig. 2 is a vertical sectional view taken through the same;

Fig. 3 is a horizontal sectional view on the line

III—III of Fig. 2;

Fig. 4 is a detail sectional view taken through the jaw clamp on the line IV—IV of Fig. 2;

Fig. 5 is a vertical sectional view taken through a wood shoe heel of a type to which the present 55 invention is particularly adapted.

Referring more particularly to the drawing, there has been disclosed in Fig. 5 a wood shoe heel, designated generally by the numeral 1. The heel is so constructed that it may be fastened by means of nailless devices to an associated shoe body, in accordance with the disclosures in the aforesaid patent to Eichhorn. In attaining these ends, it is necessary to produce in the heel in a predetermined location a transversely extending bore or opening 2 which extends inwardly from 10 the breast surface 3 of the heel, the said bore or opening intersecting a pair of spaced relatively narrow slots 4, which extend downwardly into the heel from the top or seating surface 5 thereof. It is essential that the bore or opening 2 should 15 be accurately located within the heel body and it is to the attainment of this purpose that the gaging fixture 6 comprising the present invention is particularly addressed.

The said fixture, in the specific form of the 20 invention herein disclosed, comprises a metallic body formed to include a flat horizontal base 7, an upstanding vertical wall 8 and a short forwardly projecting and overhanging top wall 9.

The front surface of the vertical wall 8 is provided, intermediately of the height thereof with 25 a horizontally disposed cross saddle 10, threaded bolts or screws 11 being employed at the ends of the saddle to unite the same firmly in connection with the wall 8. The bowed intermediate 30 portion 12 of the saddle 10 is disposed in registration with a slot or recess 13 formed in the front of the wall 8. This bowed portion is provided with a set of four parallel openings adapted 35 to adjustably and slidably receive positioning pins 14. The rear ends of these pins are connected with a back plate 15, while the forward ends thereof project slightly and adjustably in advance of the front wall of the saddle 10, coil 40 springs 16 being disposed to surround said pins and are located between the plate 15 and the back of the saddle 10. To vary the extent of projection of the forward ends of the pins 14 with respect to the front of the saddle, the wall 8 is formed with a threaded opening designed for the 45 reception of a threaded adjusting screw 17. By manually rotating this screw, the same will be brought into engagement with the plate 15, causing the latter to move in and out against the compression of the springs 16, and thereby varying 50 the extent of projection of the forward ends of the pins 14 with respect to the front of said saddle.

The screw 17 is equipped with a lock nut 18 in order to maintain the permanency of its adjusted positions. The top and bottom surfaces of 55

the saddle 10 are recessed to receive spaced tongues 19, secured in place by threaded fastening means 20. The tongues 19 are so spaced that they may be received within the slots 4 provided in the heel 1, while the forward ends of the pins 14 serve as adjustable stops for regulating the clamping positions of the heel within the fixture.

In order to hold the heel in the dotted line position disclosed in Fig. 2, the forward end of the base 1 is provided with a pair of spaced apertured lugs 21 which receive a rock shaft 22 carrying at one end an actuating handle 23. Mounted on the shaft 22 between the lugs 21 for rocking movement in unison therewith is a clamping jaw 24. This jaw is formed to include a substantially V-shaped mouth 25 having angular surfaces 26 adapted for ready engagement with the rounded curvature of a shoe heel. The surfaces 26 may be covered by fabric, as indicated at 27, to protect a wood heel from damage when clamped in the fixture. It will be seen that by actuating the handle 23, the jaw 24 may be readily rocked into holding engagement with the outer surfaces of a shoe heel blank mounted on the tongues 19, and moreover by the application of pressure to the handle, the seating surface 5 of the heel will be brought into and held in positive contact with the forward ends of the adjustable positioning pins 14.

The top wall 9 of the frame is formed with an opening 28 in which is positioned a guide bushing 29, the said bushing being provided with a longitudinally extending guide opening 31 through which may be inserted a drill or bit (not shown) in order that the drilling or boring tool may be fully and properly guided to produce the bore or opening 2 in the wood heel in the proper plane. With the use of this instrumentality, high accuracy in workmanship is obtainable and likewise the time required in performing the operation is greatly reduced.

What is claimed is:

1. A drill fixture comprising a frame formed to include horizontally disposed top and bottom walls and a connecting vertical wall, a horizontally extending saddle carried by said vertical wall, said saddle including a gaging face, horizontally adjustable work positioning means movably carried by said vertical wall and saddle, said means projecting beyond said gaging face, a work supporting tongue projecting horizontally from said saddle, pivoted clamping means carried by the bottom wall of said frame for maintaining a body to be drilled on said tongue and in engagement with said adjustable positioning means, and a vertical drill guide carried by the top wall of said frame in registration with said tongue.

2. A drill fixture comprising a frame including top and bottom walls and a uniting vertical wall, a horizontal saddle member carried by said vertical wall, spaced tongues projecting forwardly from said saddle and adapted to be received within slots provided in the seating surface of a wood heel, adjustable means for varying the spacing between the seating surface of a wood heel supported on said tongues and said saddle, a movable clamping jaw operating to engage the sides of a wood heel positioned on said tongues and to maintain the heel in relatively immovable engagement with said positioning means, and a drill guide passing vertically through the top wall of said frame.

3. A fixture for facilitating the drilling of

openings in shoe heels comprising a frame including horizontal top and bottom walls and a uniting vertical wall, a heel support carried by said vertical wall, adjustable means for varying the operative positions of a heel placed on said support, a movable clamping jaw carried by said bottom wall and engageable with the sides of a heel carried by said support to retain the heel against movement thereon, and a drill guide passing vertically through the top wall of said frame in registration with a heel positioned on the support.

4. A drill fixture for facilitating the drilling of openings in shoe heels, comprising a frame including substantially horizontally disposed top and bottom walls and a uniting vertical wall, heel supporting means carried by said vertical wall and operative to removably support a heel engaged therewith in a substantially horizontal position with the breast surface of the heel facing upwardly, a movable clamping jaw carried by said frame for maintaining a heel positively on said support, and a drill guide extending vertically through the top wall of said frame and disposed in registration with the breast surface of a heel positioned on said support.

5. A fixture for facilitating the drilling of openings in shoe heels comprising a frame, a heel support carried by said frame and including a plurality of spaced tongues disposed to enter slots provided in the seating surface of a heel, said tongues being so arranged that when a heel is positioned thereon, the breast surface of the heel will face upwardly, movable means carried by said frame for clamping a heel on said support, and a vertical drill guide formed with said frame and disposed in registration with the breast surface of a heel carried by said support.

6. A fixture for facilitating the drilling of openings in shoe heels, comprising a frame, means for adjustably retaining a shoe heel in a substantially horizontal position within said frame with the breast surface of the heel facing upwardly, and a drill guide formed in connection with said frame and disposed in vertical registration with the breast surface of a heel confined in said frame.

7. A fixture for drilling holes comprising a frame, an adjustable heel support carried by said frame, said support including a pair of spaced tongues arranged to enter slots provided in the seating surface of a heel, a movable clamping jaw carried by said frame and engageable with the sides of a heel to confine the latter on said support, and a drill guide formed in connection with said frame and disposed in registration with the central portion of the breast surface of a heel removably confined on said support.

8. A heel drilling fixture comprising a heel support, a drill guide, means for maintaining a wood heel positioned on said support with the breast surface thereof presented to said drill guide, and means cooperative with said support for holding the heel with the breast surface thereof in predetermined longitudinal and transverse positions relative to the drill guide.

9. A heel drilling fixture comprising a frame including a pair of parallel walls and a connecting wall extending therebetween, a drill guide extending perpendicularly through one wall of said pair, a plate provided on said connecting wall, said plate being formed for insertion into a slot formed in the seating surface of a heel, adjustable means for limiting the degree of insertion of said plate in the slot, and means formed in connection

with the other wall of said pair of walls for clamping the heel in engagement with said adjustable limiting means.

5 10. A heel drilling fixture comprising a frame, a drill guide formed in connection with said frame, means cooperative with said frame for supporting a heel with the breast surface thereof perpendicular to and in registration with said drill guide, positioning means engaging the seat-

ing surface of said heel to control the distance from the edge of the seat surface to the point on the breast surface in registration with said drill guide, and a clamping device to hold the heel in engagement with said positioning means, said clamping device determining the lateral positioning of said heel relative to said drill guide.
